UNITED STATES PATENT OFFICE

ALBERT N. EATON, OF OMAHA, NEBRASKA

BARREL-CLEANING APPARATUS

Application filed November 1, 1928. Serial No. 316,406.

The present invention relates to improvements in barrel cleaning apparatus, and has for an object to provide an improved apparatus for cleaning the rust, scale, grease, old paint and other foreign substances from barrels, particularly metal barrels.

Another object of the invention is to provide an improved apparatus of this character in which the cleaning of the barrels may be conducted economically and efficiently.

A further object of the invention is to provide an improved apparatus, wherein barrels of different diameters may be cleaned without requiring any modification of the constructions of the parts and by admitting the various different types of barrels after minor adjustments have been made.

A still further object of the invention is to provide an improved barrel cleaning apparatus in which the parts are grouped into a compact construction, operating simply and reliably, and the construction and arrangement of the parts admitting of the barrels being quickly placed in, and removed from, the apparatus.

A still further object of the invention is to provide an improved barrel cleaning apparatus in which the cleaning operation is reduced in point of time and the results achieved are superior to those now obtainable with present types of apparatus.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view, with parts broken away of an improved barrel cleaning apparatus constructed according to the present invention.

Figure 2 is a side view of the same, parts being broken away and parts shown in section.

Figure 3 is an end view of the apparatus.

Figure 4 is a transverse sectional view taken on the dotted line 4-4 in Figure 2 and looking in the direction of the arrow, and

Figure 5 is a similar view taken on the line 5-5 also in Figure 4.

Referring more particularly to the drawings, 10 designates a vat or container of any desired form, for instance of the U-form shown in cross section. The vat is open at its top and provided with reinforcing angle irons 11 along the margin portions of its side walls. The vat may be supported in any appropriate manner, for instance by means of cradles 12 having the legs 13 resting upon the floor. Within and adjacent the lowermost portion of the vat 10 is a steam pipe or coil 14 having its ends brought out, as indicated in Figure 1, and connected with a boiler or other source of steam supply (not shown), whereby a circulation of steam through the pipe 14 may be had to raise the temperature of the cleansing solution in the vat 10.

This solution may contain chemicals, such as caustic soda and the like. In Figure 1, a drain pipe 15 is shown as connected to the vat for the purpose of drawing off the solution at desired times and the drain pipe may be provided with a suitable cut-off valve (not shown).

Two shafts 16 and 17 are suitably journaled in the end walls of the vat and extend substantially the entire length of the vat and preferably through one of the end walls, as shown in Figures 1 and 3, where such shafts are respectively provided with fixed pinions 18 and 19 disposed in mesh with an intermediate idler pinion 20, whereby the shafts 16 and 17 may rotate in the same direction.

One of the shafts, for instance, the shaft 16 carries a pulley 21 engaged by the belt 22, whereby the shafts are driven from any appropriate source of power. Within the vat 10 is disposed a brush shaft 23 carrying the rotary brush 24. The shaft 23 is supported for swinging movement about the shaft 16 as a center and for this purpose the end portions of the shaft 23 are carried by arms 25, such as shown in Figures 1 and 5, while the intermediate portions of the shaft 23 are pivotally mounted in triangular plates 26, such as shown in Figure 4. The brush 24 is preferably a stiff wire brush, and as shown

in Figures 1 and 2, two or more such brushes may be employed in the same vat 10, it being understood that the embodiment of the invention shown in the drawings is for the accommodation of two barrels whereby two such barrels may be washed simultaneously. The barrels are indicated at 27 and are adapted to rest upon the rollers 28 and 29 which are fixed to the shafts 16 and 17.

10 The triangular bracket arms 26, shown in Figure 4, are adapted to carry a counter shaft 30. Pinions 31 and 32 are splined to the counter shaft 30, the pinion 31 being disposed at all times in mesh with a pinion 33 fixed upon the shaft 16; and the pinion 32 being in mesh at all times with a small pinion 34 on the brush shaft 23. By this means it will be understood that a gear ratio is provided, whereby the brush shaft 23 will rotate at a much higher speed than the drive shaft 16.

As best shown in Figure 4, a rod 35 depends into the vat and is connected at its lower end to an arm 36 having connection to one 25 of the triangular frame plates 26. The upper portion of the rod 35 is provided with threads, as indicated at 37 to receive an adjusting nut 38 having an extension handle 39 for convenience in its rotation. The threaded portion 30 of the rod extends upwardly through a cross beam 40 disposed across the vat, and the nut 38 is adapted to rest upon this beam 40.

Upon the rear wall of the vat 10 vertical cleats 41 are secured and provided with a plurality of eyes 42 to removably receive the pins 43. The cleats are further provided with recesses 44, shown in Figures 4 and 5 to receive the pivot rods 45 of the hold-down frames or devices. These frames consist of 35 the side styles or bars 46 and the transverse brace rods 47. Upon the side frame members 46 a pair of L-shaped arms 48 are secured and provided with transversely extending connecting rods 49. One such rod 49 is positioned, when the device is in the raised condition, shown in Figure 4, to receive the hook or keeper 50 pivoted at 51 upon the bracket 52, carried by the vat or other appropriate part.

50 Attached to the side frame members 46 are plates 53 in which are carried pivot rods 54. Roller carrying frames 55 are pivotally attached to the plates 53 through the pivot rods 54, said frames carrying rollers 56. 55 Each frame preferably carries four rollers, as shown in Figures 1 and 2.

In operation, the vat is filled up to a suitable level with a chemical or other cleansing solution. The steam may or may not be turned on through the coil 14 to heat this solution to a desired temperature. Initially the hold-down devices are in the raised position, shown in Figure 4, where they are held by the hooks or keepers 50, so that the 60 undivided attention of the operator may be

given to the work of introducing the barrels into the upper ends of the vats and onto the supporting rollers 28 and 29. It will be seen from Figure 1 that four such rollers are provided, two on each of the spaced shafts 16 and 17. These shafts being rotated in the same direction, will cause the barrel 27 to also rotate within the vat and within the solution. The hold-down devices are lowered upon the barrel to the position indicated in Figure 5, and the required pressure may be exerted upon these hold-down frames to keep the barrels against the rollers 28 and 29 and against the cleansing brush 24, which is rotated at a high speed owing to the gearing referred to. It will be noted that the brush 24 is rotated in an opposite direction to that of the barrel 27, whereby to increase the cleansing action. The crank handle 39 may be rotated in one direction to draw the rod 35 upwardly, causing the triangular plates 26 and the entire brush assembly to be raised toward the external surface of the barrel 27 with which such brush contacts. When the crank 39 is rotated in the opposite direction, the parts will be released and the brush and its assembly will drop by gravity away from the barrel. The degree of the pressure of the brush may be thus regulated.

In Figure 4 I have shown a barrel of large diameter, as compared, in Figure 5, with a barrel of smaller diameter. It will be noted by comparison of these figures that the pivot bar 45 of the hold-down device occupies a position in the cleats 41 one notch higher in Figure 4, than in Figure 5. The hold-down frame may be adjusted to any of the notches 44 by first removing the pin 43 and again inserting the pin in front of the bar 45, after the same has been deposited in the selected notch. In this way all standard sizes of metal barrels may be cleansed in the vat.

I do not wish to be restricted to the size, form and proportions of the various parts, and obviously changes could be made in the construction herein described without departing from the spirit of the invention, it being only necessary that such changes fall within the scope of the appended claims.

What is claimed is:-

1. In a barrel cleaning apparatus, a vat, barrel supporting means in the vat, barrel cleansing means in the vat, a notched bracket, a pin for closing the notches, and a pivoted hold-down device for the barrel having a rod to selectively fit in the notches of said bracket and held removably therein by said pin.

2. In a barrel cleaning apparatus, a vat, barrel support and brushing means therein, brackets, a hold-down frame adjustably and pivotally held by said brackets, a catch to hold the frame elevated, and a supplemental roller frame carried by said hold-down frame.

3. In a barrel cleaning apparatus, a vat, barrel support and brushing means therein, brackets on the vat, a hold-down frame pivotally carried by said brackets, and a supplemental roller frame carried by said hold-down frame for engaging the upper portion of the barrel.

5 In testimony whereof, I have affixed my signature.

ALBERT N. EATON.
